UNITED STATES PATENT OFFICE.

GEORGE REMINGTON WRIGHT, OF VANCOUVER, BRITISH COLUMBIA, CANADA.

IGNITION DEVICE.

1,411,703.

Specification of Letters Patent.

Patented Apr. 4, 1922.

Application filed July 23, 1917. Serial No. 182,313.

To all whom it may concern:

Be it known that I, GEORGE R. WRIGHT, a subject of the King of England, residing at Vancouver, British Columbia, Canada, have 5 invented certain new and useful Improvements in Ignition Devices, of which the following is a specification.

The present invention has relation to improvements upon the timer or commutator 10 device for internal combustion engines as disclosed by my previous patent No. 1,251,162 granted December 25, 1917.

While these improvements embody principles of construction and operation similar 15 to my previous invention of the aforesaid patent, they involve certain novel features which provide means for overcoming many difficulties heretofore experienced and which means from the practical standpoint, possess 20 important advantages looking toward (1) an accurate yet automatic control of the point of ignition of the gases in timed relation to piston movement, (2) a reduction in the deterioration of the circuit terminals due 25 to arcing, (3) a proper facility of movement of the traveling brush carrier, and lastly but importantly, a greater effectiveness 30 in the action of the governor elements such that the leverage function of the latter 35 for producing relative movement of the brush carrier to cause advancing of the spark will increase in proportion to the increase of tension or resistance offered by the means provided to automatically effect retarding of the spark at low speeds of the engine.

These phases of the invention will be taken up seriatim as the description of the respective features of construction giving 40 rise thereto are set forth.

For a full understanding of the invention, reference is to be had to the following description and accompanying drawing, in which,

45 Figure 1 is an elevation showing the timer case in adjusted position upon the cylinder front cover.

Figure 2 is a vertical sectional view, showing in full lines the position of the governor 50 elements under retarding spark condition, and in dotted lines, under full advance condition.

Figure 3 is a sectional view on the line 3—3 of Figure 1.

Figure 4 is a front elevation of the rotor 55 assembly.

Figure 5 is a perspective view of one of the governor weights, including a slight modification for accommodating a spring retarding means.

Figure 6 is a fragmentary sectional view on the line 6—6 of Figure 3.

Throughout the following detail description and on the several figures of the drawings, similar parts are referred to by like 65 reference characters.

While I have illustrated the embodiment of this device as particularly adapted to the Ford motor construction and ignition system, it will be apparent to those skilled in 70 the art that it is capable of other adaptations without material change of details of construction.

In the drawing 1 designates the cylinder 75 front cover against the face of which the timer case 2 of this invention is held by the regular-equipment spring 3. One of the very important points in the assembly of the equipment of motor vehicles is the proper positioning, relatively of the timer 80 case, for it must be so disposed that at extreme full retard the spark or ignition will take place a few degrees past dead center, this being controlled where the case is of the ordinary movable type by the adjustment of the spark lever connections. In the present instance however, the timer case 2 is relatively stationary and is removably held fixed by the spring 3 which at its outer 85 end seats in a transverse groove 4 in the case 5, the walls of the said groove converging toward its base so as to produce a wedging of the spring in place as its fastening bolt 3' is tightened. This particularly 90 shaped groove compensates for any variation in the width of springs 3 as manufactured, and takes up lost motion that may occur incident to the variation. As will be noticed in Figure 1, this groove furthermore 95 conforms to the narrowing taper of the outer end of the spring, all of which is particularly designed to make the arrangement fool-proof in that it is impossible for one unskilled in the technical knowledge of these mechanisms to make faulty replacement 100 after installation. Since there are no link or lever connections for this case subject to wear, as in the Ford equipment, once the

105

position of the case cover 5 is determined, which is generally at the factory, it requires no further adjustment during the life of the device, but should it be found that a particular motor after continuous use or for other structural reasons necessitates the slight shifting of the terminals of the case so that the most retarded spark will occur at the proper point hereinbefore referred to, 5 the mechanician may accomplish the adjustment by loosening the cover screws 6 and shifting the case in either direction from the intermediate normal, depending upon whether the ignition point is to be advanced 10 or retarded, said cover being suitably slotted as indicated at 7, and preferably marked adjacent to one of the slots with the letters R—N—A— representing retard, normal and advance, respectively. 15 The insulating material of the body of the timer case is fiber or better "bakelite" and in this the segments 8 are inset, the usual binding posts 9 being arranged exteriorly. The application or removal of the 20 case in this arrangement is extremely simple requiring only the slackening off and tightening of the bolt 3', and engagement in or disengagement from the groove 4, of the spring 3, and the accurate relationship 25 of the segments with respect to firing points in the cylinder is thereby fixedly secured.

Passing now to the next feature, namely the rotor assembly, 10 designates a casing which is loosely journaled upon the sleeve 35 11 which is fixed on the cam shaft 12 by a pin 13, and the cap 14 and nut 15 of the Ford equipment. It may be here stated that I have had in mind when devising this 40 construction of my invention the desirability of eliminating any necessity whatever for a change in the motor construction as regularly placed on the market so that the device may be applied by an unskilled person ignorant of the use of special tools 45 or the general methods of assembling motor vehicles. The casing 10 is provided with the cover plate 16 and this is closed against access to the contents, preferably by riveting the pins or posts 17 arranged diamet- 50 rically opposite to each other, said posts having a further function as hereinafter described.

Pivottally secured at opposite sides of the sleeve are independently operable opposing 55 governor weights 18, one of which is best seen in Figure 5, and the special or particular shape of which is important, as pointed out in the following description. The weights cooperate or engage with the respective posts 17 through the instrumental- 60 ity of which the casing 10 is shifted relatively on the sleeve for the purpose of advancing the brush 19, carried in the peripheral pocket 20 so as to slightly project 65 therefrom under action of a spring 21, to

contact earlier with the segments 8 of the stationary case 2. This actuation of the casing takes place incident to the centrifugal action of the weights which are caused to swing about their pivots more or less 70 according to the speed of the engine or shaft 12 and in such swinging the weights move outwardly in a radial direction, sliding against the posts, and at the same time in a circumferential direction. The retarding of the spark is automatically effected 75 obviously by the reverse action under the influence of the springs 22, each of which is connected at one end to the sleeve 11, as at 23 and to the casing 10 as at 24, the longitudinal axis of said spring normally lying 80 tangent to the shaft 12.

As regards the brush 19, it may be stated 85 that its oblongated shape is provided to insure the proper replacement whenever it is removed for any purpose, while as to material, I prefer to use suitable metal.

This brings us to the second feature of novel characteristics of this invention. It will be observed that the segments 8 are 90 very much longer than usual, in fact they extend in an arc of substantially 85° leaving a very narrow interruption between each segment which intervening portion of insulation is preferably narrower than the 95 thickness of the brush. By much experimentation I have found this to be very important as affecting the well known deleterious effect of arcing which rapidly burns away the extremities of the segments, resulting in defective operation of the ignition system. Owing to the fact that in my construction the brush at one side passes on to the next succeeding segment, practically 100 before its opposing side leaves the preceding segment there is a substantial continuity 105 of flow of the current eliminating the arcing of the usual constructions and prolonging the life of the vibrator coils and contacts.

Again in an arrangement of this character it is very desirable that friction between the brush and the stationary case be reduced to a minimum so that the brush carrying member will be sensitive in action 115 under the actuation of the governor device. This is a condition obtained by the use of metal against metal, the brush having a substantially complete metal track on which to operate.

Furthermore the prolonged length of the segments is very advantageous as affecting quick firing in "cranking over" the engine, the extent of movement of the crank shaft required being noticeably reduced as compared with action of the former types of commutator constructions.

Reverting now to the special shape of the weights, it is of course an obvious requirement that the greater mass of the weight 120

normally lie near the center of rotation of the rotor so that the leverage action will be least effective under centrifugal action, during slow speeds. As the weights 18 are 5 arranged the mass gradually moves outwardly of this center, such movement with the accompanying circumferential movement causing the shifting of the casing 10, against the retarding influence of the springs 10 22. I discovered that where the weights are shaped as in the construction of my previous patent, that while the gradual advance of the brush at slower speeds was effective as desired, at higher speeds the 15 leverage of the centrifugal force was insufficient to overcome the increase of tension of the retarding springs to the extent desirable for highest efficiency necessary to cause the proportionate greater advance required of the brush contact. This was due to the fact that the spring tension increased in approximately an exact ratio as its length increased when stretched during rotation and the leverage of the weights did 20 not increase in sufficient relative proportion. This is overcome by providing the weight with a greater mass of metal at its free end but so shaping it that this said metal becomes rapidly effective as the weight 25 swings about its pivot bringing the mass farther away from center while normally the greater mass lies near the axis of rotation.

While the desired result is accomplished 35 by the form of weight as particularly shown in the annexed drawing, I do not wish to be confined to such shape, any other producing the same effect being comprehended within the scope of my invention.

40 Briefly summarizing the operation of the device, and referring to Figure 2, when the engine is started, the governor weights occupy the full line position shown in said figure, said weights gradually shifting toward the dotted line position as the speed 45 of the engine increases and in so doing carrying the brush carrier or casing 10 around in the direction of the arrow, thereby changing the relative position of the brush 50 with respect to the segments 8 of the case.

55 2. In like manner as the speed of the engine reduces, the brush gradually resumes its normal retarded position under the action of the restoring springs 22. The result of this action is that the engine operates always at its maximum efficiency according to the speed of actuation and because of the automatic control thus provided the transmission changes of gear ratio are accomplished 60 very smoothly, even by the most unskilled operator.

It is to be understood that changes may readily be made in the details of construction as above described without departing

from the spirit of the invention and within 65 the scope of the annexed claims. For example, instead of using the expansion spring type above described, each weight may be provided with a recess or seat to receive a compression spring 22', the outer end of 70 which is arranged to act against a nib or boss 22" on the casing 10 to accomplish the desired result.

Having thus described my invention, 75 what I claim as new is:

1. Ignition means for internal combustion engines, comprising a relatively stationary member, a rotating member, a shaft on which said rotating member is mounted, contact terminals carried by said members, 80 a governor device for effecting relative movement between the relatively stationary and rotating members during operation including a weight pivotally connected at one end to the shaft aforesaid, the other end being free to shift under centrifugal action about said pivot and circumferentially of the shaft and of the rotating member, and means arranged to be impinged by the weight to produce the relative movement 85 between the parts as aforesaid.

2. Ignition means for internal combustion engines, a case having a plurality of contact terminals and provided with a groove, a retaining member attached to the engine and 95 interengaging in the groove aforesaid for determining the position of the terminals and holding the case relatively stationary, a rotating contact carrying member arranged to cooperate with the case aforesaid, and 100 means for controlling the position of the carrying member relatively to the case.

3. Ignition means for internal combustion engines, a case having a plurality of contact terminals, a retaining member connected at 105 one end to the engine and at its other end tapering and engageable with the case, said case having a recess conforming to the shape of the tapering end of the holding member, whereby to determine the position of the 110 case terminals and hold the case relatively stationary, and a rotating contact carrying member arranged to cooperate with the case and shiftable relatively thereto.

4. Ignition means for internal combustion engines, a case having a plurality of contact terminals, a retaining spring connected at one end to the engine and having its other end engageable with the case, said case having a part adjustably connected thereto with which the spring interlocks whereby to permit of adjustment of the case with relation to said part to allow for variation of the relative position of the terminals, said case being held relatively fixed by said 115 spring upon determination of an adjustment thereof, and a contact carrying rotor operable within the case.

5. Ignition means for internal combustion engines, a case having a plurality of contact terminals, said case having shiftable cover, and fastening means for determining the relative position of the cover with respect to the body of the case, the cover also having a transverse groove therein, a re-

taining member connected to the engine and engageable with the cover groove for locking the case in relatively stationary position, 10 and a rotating contact carrying member arranged to cooperate with said case.

In testimony whereof I affix my signature,
GEORGE REMINGTON WRIGHT.
